VIBRATION INSULATOR FOR SPACING APART OVERHEAD WIRES

John Edward Gill, Brentwood, and Edward William Fletcher, Surbiton, England, assignors to Balfour, Beatty & Co. Limited, London, and Andre Rubber Company Limited, Surbiton, England, both British companies

Application November 18, 1957, Serial No. 48,529

Claims priority, application Great Britain June 4, 1957

Term of patent 14 years

(Cl. D26—10)

Figure 1 is a perspective view as seen from above and one side of a vibration insulator for spacing apart overhead wires showing our new design;

Figure 2 is a perspective view thereof as seen from below and from the other side;

Figure 3 is an enlarged fragmentary perspective view of one end thereof as seen from above; and

Figure 4 is an enlarged fragmentary perspective view of the other end thereof as seen from below.

We claim:

The ornamental design for a vibration insulator for spacing apart overhead wires, substantially as shown.
